BLADED ROTOR AND THE LIKE FOR AXIAL FLOW FLUID MACHINES

Edward A. Stalker, 406 N. Farragut St.,
Bay City, Mich.Filed June 4, 1958, Ser. No. 739,832
6 Claims. (Cl. 253—77)

My invention relates to bladed rotors and the like for axial flow compressors, turbines and the like.

An object of my invention is to provide an economical and light weight rotor particularly adapted to sheet metal construction.

Another object is to provide a rotor wherein the joints are readily inspectable.

Still another object is to provide a bladed structure wherein the blades are supported on a single disk by a simple connection.

Other objects will appear from the specification, appended claims, and accompanying drawings.

The above objects are accomplished by the means illustrated in the accompany drawings in which—

FIG. 1 is an axial view of a fragment of a rotor according to the subject invention;

FIG. 2 is a fragmentary section on line 2—2 in FIG. 1;

FIG. 3 is a fragmentary section on line 3—3 in FIG. 2;

FIG. 4 is a section on line 4—4 in FIG. 2;

FIG. 5 is a fragmentary section on line 5—5 in FIG. 2;

FIG. 6 shows a fragment of the inner end of a hollow blade with the legs spread apart before engagement with the disk of the rotor; and

FIG. 7 shows a fragment of the inner end of a blade whose legs are integral with the blade surface and spread apart before engagement with rotor disks.

In this invention the blade may be solid or composite with a stem bonded interiorly of the blade shell. Such a composite blade will usually be hollow. The stem extends radially inward through the rim means and engages the rim mechanically. It may also be bonded to the disk by fused metal, braze metal for instance.

Referring now to the drawings the rotor is indicated generally by 10. It comprises the blade 12 and the hub means 14.

The hub means 14 comprises the hollow rim means 16 and the rotor blade central support disk 20 positioned between the leading and trailing edges of the blades.

The blades are spaced peripherally, FIGS. 1 and 3, and each comprises a blade shell and a root portion integral therewith preferably of a thicker wall than the shell. The root portion fairs into the shell by a generous fillet, and a stem 22 fixed internally of the blade and extending radially inward through the rim of the rim means to a junction with the rotor disk for support thereby.

The stem has the two legs 23 and 24 which have the tenons 30 and 32, FIGS. 1, 2 and 5, which pass through openings 34 in the disk. These are peripherally spaced about the support disk. The tenons fit closely to the sides of the openings and to each other in side by side relation.

Each leg preferably bears on the disk which is received between them and is preferably bonded thereto by fused metal preferably braze metal. The stem and disk form a simple light structure capable of supporting the blade against the forces arising from its rotation in use. The disk may also be reinforced by a ring 40 bonded to the disk.

The disk preferably has peripherally spaced notches in its periphery into each of which the inner end of the root portion of a blade fits and is preferably bonded to give additional side support to the blade means.

The rim means comprises the rim segments 42 between

2

blades at their root portions (see FIGS. 1 and 3), the rim side rings 44 and 46, and the angles 47 and 48 fixed to the rim segments and preferably bonded to the root portions of the blades. Preferably the rings have flanged openings 50 for stiffening the rings and for access to the legs and joints of each stem with the hollow rim means which is closed to radial view by the peripheral portions of the disk.

The rim means extend from front to rear of the rotor and from blade to blade to sustain variations in fluid pressure. The rim means is secured to the disk for support thereby.

The disk is metal to provide rigidity and homogeneous strength properties in all radial directions so that it can support the blades bearing against the radially outward sides of the disk holes for support against the centrifugal forces. The disk is preperforated with generally rectangular holes directed radially, that is having their major dimension along the radius. The tenons would have a cross section at the disk conforming to the shape of the holes. This rectangular cross section is necessary to provide adequate shear strength in the tenon. Thus adequate strength is provided while retaining the low cost feature of a generally flat root portion of the blade including the legs and tenons.

The stem is first formed with the legs spread apart as shown in FIG. 6 providing a gap 54 just large enough for the stem to straddle the disk. The legs are then pressed toward each other and through the hole in the disk.

The blades may have the legs integral with a blade surface including that of a solid blade with tenons formed in the legs as shown in FIG. 7. The tenons are to engage the disk in the same manner as of FIGS. 2 and 5.

The disk may be attached to a shaft means 57 by bolts 58 spaced peripherally about the disk, for instance. The rotor rotates with the shaft about the axis of symmetry of the rotor or disk.

It will now be clear that I have provided a light weight and economical rotor. The blades are simple to make since they require no costly and heavy machined rotor rims. Furthermore the connections of the blades to the disk are easily inspected.

While I have illustrated specific forms of the invention, it is to be understood that variations may be made therein and that I intend to claim my invention broadly as indicated by the appended claims.

I claim:

1. In combination in an axial flow rotor adapted to change the pressure of a fluid, a metal sheet defining a blade support disk having an axis of rotation and having a plurality of preperforated peripherally spaced holes therethrough, a plurality of blades peripherally spaced about said disk with the spans thereof extending radially outward from said disk relative to said axis, each said blade having an integral leg positioned along an axially facing side of said disk with a tenon thereof in a said hole in radially outward bearing relation on said disk for the engagement thereof by said tenons to support the blade by said disk against centrifugal force in operation of said rotor, each said tenon being of generally flat form extending in the general radial direction defining a generally rectangular cross section thereof at said disk to provide sufficient radial extent of said tenon to support said blade against centrifugal force in use, said preperforated holes having a generally rectangular cross section conforming closely to said cross section of said tenon for the receipt thereof within said holes in close fitting relation, said tenons being brazed to said disk at the sides of said holes thereof and rim means secured to said disk, said rim means encircling said disk with the rim thereof extending from

front to rear of said blades and from blade to blade to sustain variations in said fluid pressure.

2. In combination in an axial flow rotor, a metal sheet defining a blade support disk having an axis of rotation and having a plurality of preperforated peripherally spaced holes therethrough, a plurality of axial flow blades having root portions at their radially inner ends and being peripherally spaced about said disk with the spans thereof extending radially outward from said disk relative to said axis, each said blade having legs fixed in said blade and straddling said disk, said legs having tenons side by side in a said hole in bearing relation on said disk for the engagement thereof by said tenons to support said blade by said disk against centrifugal force, said tenons being bonded to each other and to said disk, each said tenon being of generally flat form extending in the general radial direction defining a generally rectangular cross section thereof at said disk to provide sufficient radial extent thereof to support said blade against centrifugal force in use, said preperforated holes having a generally rectangular cross section conforming closely to said cross section of said tenon for the receipt thereof within said holes in close fitting relation, and rim means at the root portions of said blades secured to said disk, said rim means encircling said disk with the rim thereof extending from front to rear of said blades and from blade to blade to sustain variations in said fluid pressure.

3. In combination in an axial flow rotor adapted to change the pressure of a fluid, a metal sheet defining a blade support disk having an axis of rotation and having a plurality of preperforated peripherally spaced holes, a plurality of composite blades peripherally spaced about said disk with the spans thereof extending radially outward from said disk relative to said axis, each said blade having a hollow blade shell and a stem therewithin bonded to the internal surfaces thereof, each said stem having integral legs straddling said disk, said legs having integral tenons side by side in a said hole in bearing relation on said disk for the engagement thereof by said tenons to support said blade against centrifugal force, each said tenon being of generally flat form extending in the general radial direction defining a generally rectangular cross section thereof at said disk to provide sufficient radial extent thereof to support said blade against centrifugal force in use, said preperforated holes having a generally rectangular cross section conforming closely to said cross section of said tenon for the receipt thereof within said holes in close fitting relation, and rim means at the root portions of said blades secured to said disk, said rim means encircling said disk with the rim thereof extending from front to rear of said blades and from blade to blade to sustain variations in said fluid pressure.

4. In combination in an axial flow rotor, a rigid sheet of material defining a blade support disk having an axis of rotation and having a plurality of preperforated peripherally spaced holes, a plurality of axial flow blades having root portions at their radially inner ends and being peripherally spaced about said disk with the spans thereof extending radially outward from said disk relative to said axis, each said blade having legs straddling said disk, said legs having integral tenons side by side in a said hole in bearing relation on said disk to support said blade by said disk, said side by side tenons being brazed to each other to form a brazed joint, and rim means at the root portions of said blades secured to said disk, said rim means encircling said disk with the rim thereof extending from

front to rear of said blades and from blade to blade to sustain variations in said fluid pressure, said rim means encompassing said root portions and excluding said portions from radial view, said rim means having openings in the sides thereof opposite said tenons to provide for the inspection of said brazed joints.

5. In combination in a bladed rotor for compressors, turbines and the like, a sheet of rigid material defining a central disk having a plurality of peripherally spaced holes and a plurality of blades peripherally spaced about said disk and having their spans extending radially therefrom, each said blade having integral legs straddling said disk, each said leg having integral tenons overlapping along the chordwise direction and brazed to each other along said sides and extending in the general radial direction in a said hole in bearing relation on said disk for the engagement thereof by said tenons, each said tenon being of generally flat form extending in the general radial direction defining a generally rectangular cross section thereof at said disk to provide sufficient radial extent thereof to support said blade against centrifugal force in use, said preperforated holes having a generally rectangular cross section conforming closely to said cross section of said tenon for the receipt thereof within said holes in close fitting relation.

6. In combination in a bladed structure for compressors, turbines and the like, a sheet of rigid material defining a central disk, a rim means having blade openings and encircling said disk and fixed thereto, a plurality of blades peripherally spaced about said disk and having their spans extending radially inward through said openings of said rim means along said disk, each said blade having a leg having a tenon integral therewith positioned in a hole in radially outward bearing relation on said disk for the engagement thereof by said tenons to sustain the blade against centrifugal force, each said tenon being of generally flat form extending in the general radial direction defining a generally rectangular cross section thereof at said disk to provide sufficient radial extent of said tenon to support said blade against centrifugal force in use, said preperforated holes having a generally rectangular cross section conforming closely to said cross section of said tenon for the receipt thereof within said holes in close fitting relation, each said tenon being bonded to said disk at the sides of said hole therein, said blades bearing on said rim means at said holes for support against forces transverse to said span and being bonded to said rim means.
